[57] **CLAIM**

The ornamental design for packaging container for syrup or the like, substantially as shown and described.

DESCRIPTION

FIG. 1 is an elevational view of a packaging container for syrup or the like showing our new design;

FIG. 2 is an elevational view looking from the right of FIG. 1;

FIG. 3 is an elevational view looking from the left of FIG. 1;

FIG. 4 is a fragmentary top perspective view thereof; FIG. 5 is a front perspective view with the cap removed;

FIG. 6 is a rear perspective view thereof;

FIG. 7 is a top plan view thereof; and

FIG. 8 is a bottom plan view thereof.
